UNITED STATES PATENT OFFICE.

HUGH W. NUTT, OF RAINIER, OREGON.

CLAMP FOR WELL-POLISHED RODS.

1,225,674.

Specification of Letters Patent.

Patented May 8, 1917.

Application filed April 1, 1916. Serial No. 88,285.

To all whom it may concern:

Be it known that I, HUGH W. NUTT, a citizen of the United States, residing at Rainier, in the county of Columbia and State of Oregon, have invented a new and useful Improvement in Clamps for Well-Polished Rods, of which the following is a specification, reference being had to the accompanying drawings.

10 My invention relates to that class of devices used for clamping or retaining a polished rod.

The object of my invention is to provide a device of the character herein described 15 which will securely grip and hold a polished rod for wells, from dropping in after it is disconnected above, or for any other reason. I attain this object as well as other advantages, by the construction, combination and arrangement of parts illustrated 20 in the accompanying drawings which form a part hereof.

Figure 1 is a front elevation of my device.

25 Fig. 2 is a left side view of same.

Fig. 3 is a sectional view on the line 3—3 of Fig. 1.

Fig. 4 is an elevation showing casing head, tubing and polished rod of a well, 20 with my device secured in operative position on the rod.

Like numerals refer to like parts in all views.

The clamp is composed of two members 25 5—5' of suitable length, and these members have curved jaws 6—6' at their upper ends provided with teeth 7—7'. Openings 8—8' extend through the members at the base of each jaw. A bolt 9 extends through the 30 opening 8' of the member 5' and a bolt 10 extends through the opening 8 of the member 5. A strap 11 with openings near its ends to allow the passage of the bolts through it, connects the bolts at one end 35 in pivotal position. This strap is secured in position by a pin 12' in the bolt 9 and by a nut 13 on the thread 14 of the bolt 10. On the opposite side of the members 5—5' a second strap 15 is provided. This strap 40 has an opening near one end through which the bolt 9 extends and is secured therein in pivotal position by the pin 12. The opposite end of the strap 15 has a slot 16 adapted to allow the strap 15 to engage the bolt 10 in pivotal position. This end of the strap

is retained on the bolt 10 by means of a bolt head 17.

In Fig. 4 is shown a well casing head 18. Within this is a stuffing box 19 and within the latter is seen the head 20 of the 60 tubing 21. The polished rod 22 extends through the usual packing downward into the tubing 21. The polished rod is provided in suitable sections for use as the pumping or boring progresses. The clamp is here 65 shown gripping the polished rod 22 and its members engaging the upper end of the tubing head 20. The curvature of the jaws 6—6' is arranged so that it shall be eccentrical to the pivot centers 9 and 10 and in a 70 pre-determined arc so that the jaws are adapted to engage the opposite sides of an object, such as the rod, which is between them. The curvature is further arranged to allow a pre-determined spread of the 75 jaws so that objects, like rods of varying sizes, can be placed between them and the jaws will also operate to grip as herein described. This arrangement is also related to the length of the arms, inasmuch as they 80 must engage the bearings below them, that is, the well tubing head in this instance, at the same time that the jaws grip the rod. The jaws are operative without the teeth but these no doubt add to the strength of the 85 jaw grip.

It will now be seen that when it is desired to hold the polished rod from slipping downward the strap 15 is raised and the clamp placed about the rod 22. The strap 90 15 is then lowered into pivotal engagement with the bolt 10 and by moving the lower ends of the members 5—5' inwardly the clamp can be dropped down the rod 22 until the members 5—5' spread outwardly and 95 their lower parts engage the tubing head 20. Thereupon the jaws are actuated into engagement with the rod 22 and retain it firmly within the tubing in any desired position. If it is intended to change the position, the polished rod is raised and the clamp dropped and allowed to operate as just described.

It has been found that, in oil wells particularly, the polished rod becomes coated 105 with oil, and devices for holding it, usually horizontal clamps without jaws and secured by set screws, will not prevent the rod from slipping through them. This happens especially when the rod has been extended to 110

considerable length and there is much weight in its lower portion. I contend that I have overcome these difficulties and that my device will always grip and hold the rod irrespective of any weight below or whatever lubricant may be upon its surface. The device is also extremely convenient and speedy of adjustment and operation under all circumstances, and one clamp will fit any 10 rod of the sizes in ordinary use. It is also economical in cost and of convenient form to be carried about in the operator's equipment.

Having thus fully described my new and 15 useful device, I claim—

A clamping device of the character described, consisting of two oppositely disposed arms of suitable length, said arms

having oppositely disposed jaws provided with teeth and two lateral straps 20 within and near the ends of which said arms are pivotally mounted and so arranged that the gripping faces of the jaws are movable a suitable distance apart and the curvature of each is eccentric to the center of its arm 25 pivot in a pre-determined manner to adapt the jaws to engage the opposite sides of a cylindrical object between them and the arms to forthwith engage an upper end of a rigid casing surface below each, substantially as 30 described.

HUGH W. NUTT.
